CLAIM

The ornamental design for a tote as shown and described.

DESCRIPTION

FIG. 1 is a top perspective view of a tote showing our new design;

FIG. 2 is a bottom perspective view thereof;

FIG. 3 is a top plan view thereof;

FIG. 4 is a bottom plan view thereof;

FIG. 5 is a front elevational view thereof; and,

FIG. 6 is a right-side elevational view thereof.

A rear elevational view is not shown because it is identical to the front elevational view shown in FIG. 5. A left-side elevational view is not shown because it is identical to the right-side elevational view shown in FIG. 6.
